(57) **CLAIM**

The ornamental design for a nozzle, as shown and described.

DESCRIPTION

FIG. 1 is a perspective view of one design for a nozzle. FIG. 2 is a side view of the design shown in FIG. 1. FIG. 3 is a side view, opposite that shown in FIG. 2, of the design shown in FIG. 1.

FIG. 4 is a front view of the design shown in FIG. 1.

FIG. 5 is a rear view of the design shown in FIG. 1.

FIG. 6 is a top view of the design shown in FIG. 1.

FIG. 7 is a bottom view of the design shown in FIG. 1.

FIG. 8 is a perspective view of another design for a nozzle.

FIG. 9 is a side view of the design shown in FIG. 8.

FIG. 10 is a side view, opposite that shown in FIG. 9, of the design shown in FIG. 7.

FIG. 11 is a front view of the design shown in FIG. 8.

FIG. 12 is a rear view of the design shown in FIG. 8.

FIG. 13 is a top view of the design shown in FIG. 8; and,

FIG. 14 is a bottom view of the design shown in FIG. 8.

The broken lines are included to illustrate portions of the article; the broken lines form no part of the claimed design.

1 Claim, 14 Drawing Sheets
